REFRIGERATION MACHINE

Ernst Sander, Dessau, Germany

Application May 25, 1934, Serial No. 727,563
In Germany May 31, 1933

6 Claims. (Cl. 62—119)

The absorption and recovery of gases in refrigerating machines requires, as a rule, for the purpose of exchanging the solutions between the boiler and the absorber, a pumping device, which is not only a hindrance and expensive but causes leaks, particularly in connection with small refrigerating machines. The employment of partial pressure in accordance with the Platten-Munters system makes it possible to dispense with a pumping device, but on the other hand, requires a high total pressure, under which the entire plant is subjected. This causes an expensive construction of the plant, rendering it, in addition thereto also dangerous, if designed on a large scale.

By means of the present invention the drawbacks, referred to, have been obviated. The process of this invention for the absorption of gases consists therein, that the gases to be absorbed are forced to pass to the absorption liquid through walls, through which gases, but not liquids, can be forced to pass. The absorption liquid is forced to circulate by the compensation of its own fluid pressure, created by the boiling process, through the boiler and absorber; said boiler and absorber connected with each other in the lower part by means of a passage and in the upper part by means of an overflow.

In consequence of this arrangement no control or pumping gear will be required, nor will any higher pressures be necessary, than those essential for the condensation of the gases employed.

The walls, through which the gases, to be absorbed, are forced to pass prior to the admission to the absorption liquid, are of a porous nature or consist of membranes which, although absorbing the solvent, they do not allow the latter to pass through. On the other hand, they are permeable to the gases to be absorbed, with the result, that they are absorbed by the solvent. The affinity of the gas to the solvent is greater than the resistance offered by the pores.

As an appropriate porous material for the walls, porous clay products may be used as well as porous artificial stone products made from inorganic or organic masses.

In the accompanying drawing various forms of construction have been illustrated by way of example, showing suitable plans for the purpose of carrying out the process.

Fig. 1 is a diagrammatic view illustrating a complete refrigerating plant,

Fig. 2 is a similar view of an absorption device, Fig. 3 and Fig. 4 are diagrammatic views show-

ing boiling and absorbing devices housed within one container, Fig. 4 being a modified form of Fig. 3, and

Fig. 5 illustrates a semipermeable wall.

In Fig. 1 a boiler is indicated by 1, 2 is a precipitating vessel, 3 is a liquefier, 4 a nozzle, 5 an evaporator, 6 a cooler, 7 an absorber, and 8 an exchange vessel. In the boiler 1, gas is evolved by boiling a solution, for instance, methyl amine in water with the aid of a heater 11, and the boiled-out liquid flows into the vessel 2, by means of an overflow pipe 9. This causes the level of the liquid in the vessel 2 to rise, while the liquid is being pressed into the absorber 7 through the exchange vessel and further, back again into the boiler 1 by means of the exchange vessel 8. The boiled-out gas escapes from the precipitating vessel 2 through a filter-precipitator 10 and into the condenser 3 where, owing to the elimination of heat, the gas is liquefied. Upon flowing through the nozzle 4 into the evaporator 5 the gas will evaporate owing to the drop in pressure. Subsequently the gas is forced into the cooler 6, in which the liquefied gas is undercooled, and finally taken up by the solvent within the porous cylinder in the absorber 7.

For the purpose of ensuring a better exchange, a gas space may also be placed within the porous container, as shown in Fig. 2. In this way as extensive a wall surface as possible for the absorption of the gas will be formed. The wall, as shown in Fig. 2, may have, for example the form of a pot, but may also be made to consist of a tubular body inserted between two flanges. In Fig. 2 12 is a flange, 13 a porous wall, 14 a solvent, 15 a gas space or chamber and 16 is a passage or pipe for the gases coming from the evaporator. 17 is a passage or pipe from the separator and 18 a return passage or pipe to the boiler.

In Figs. 3 and 4 the boiling out process, the exchange of heat and the absorption of the gas may take place in one vessel.

In Fig. 3 19 is a metallic vessel, 20 a heating tube, 21 a heating element, and 21 a tubular body. The tubular body 21 consists, if necessary, of 45 metal, with a lower portion 22 suitably enlarged or flared out in the form of a funnel. 13 is the porous wall, allowing gas to pass through, but no liquid, by means of which the gas is admitted to the absorption liquid. 15 is the gas chamber communicating with the evaporator by means of the pipe 16. 10 is a filter intended for trapping the water which has been carried along, while 23 represents a pipe connection leading to the condenser.

This arrangement is intended to be heated electrically. The vessel 19 is charged with the solvent to such an extent that a part of the tube 21 projects from the liquid. If the electric heating element 11 is energized, the liquid (for instance water with methyl amine), contained within the heating space or chamber 21, 22, will be strongly heated. The gas will be boiled out and the boiled out water will be forced into the tube 21. The level of the liquid will always be leveled up automatically, in connection with which the boiled out water drops outside of the heating space or chamber 21. Owing to the contact with the wall 13 of the absorption chamber it will be enriched again with gas and from within the heating space or chamber 22 again attain the heating element contained within 21.

Through the medium of this cycle an excellent exchange of heat will be ensured between the boiled out water and the water enriched with gas by means of the walls of the chamber 21 and 22. At the same time part of the absorption heat will be imparted to the enriched water within the heating chamber 22. The ribs 24 serve for the purpose of discharging or carrying away the surplus heat.

In accordance with Fig. 4 the tube 21, forming the boiling space or chamber, with the funnel-shaped attachment 22, has been given the shape of a long, tubular body and attached laterally in the common vessel. The heating tube 20 is positioned centrally within the tube 21 and provided with a lateral aperture corresponding with an identical aperture in the wall of the vessel 19. This arrangement is intended to be heated by means of a flame or through the medium of hot gases. The process of boiling, of the exchange of heat, of the cycle of the liquid and of absorption is identical with that of the device in accordance with Fig. 3.

The funnel-shaped attachment 22 should suitably cover at least part of the absorption chamber or space at 13.

Instead of the porous partition 13 any other device may be employed for the absorption process and for overcoming the differences in pressure prevailing in connection therewith. The space 15 may also be filled with water taking up the gas flowing in until it is saturated and super-saturated, subsequently giving it off through the porous or gas-transmitting wall to the water circulating within the vessel 19.

In all cases there may be attached to the porous partition or membrane 13 contacts of known kind of a continuous current tension for the purpose of hindering or impeding to a greater degree the trickling of the absorption liquid, but permitting the absorption or the passage of the gas.

If necessary, several porous partitions may be disposed in series, i. e. one behind the other, for the purpose of compensating the drop in pressure between the gas space or chamber and therein, through which the circulating liquid is flowing. This particular arrangement of the semipermeable partition or wall (Fig. 5) is of general importance in processes in which on one side of the semipremable partition the liquid flows between a boiler and the absorber in a closed path, and on the other side the gas to be absorbed by the liquid contacts the partition. Preferably said liquid is permitted to boil over an obstructing wall in the boiler by pressure equalization of the liquid in the path of flow. The novel features described in the

foregoing are of special importance to small refrigerating machines.

I claim as my invention:—

1. An absorption refrigerating machine comprising a vessel provided with cooling ribs and having in the lowest part thereof a gas chamber, said gas chamber being separated from the remaining portion of the vessel by a semipermeable wall which permits only gas to pass therethrough and the vessel containing a pipe having in its upper part a boiling device and the lower part being enlarged to cover over a part of the semipermeable wall, a condenser, an evaporator, and a filter arranged in the uppermost part of the vessel to separate the water carried along by the boiled out gas, said boiled out gas passing through the condenser and evaporator to the gas chamber of the said vessel which is filled with absorption liquid to almost adjacent the uppermost end of the pipe.

2. A device according to claim 1, in which the pipe with the boiling device is arranged in the middle of the vessel.

3. A device according to claim 1, in which the pipe with the boiling device is arranged in the middle of the vessel and the semipermeable wall being arranged below the boiling device.

4. An absorption refrigerating machine comprising a vessel having in the lowest part thereof a gas chamber, said gas chamber being separated from the remaining portion of the vessel by a semipermeable wall which permits only gas to pass therethrough, said semipermeable wall being formed by a plurality of thin walls set one after another, and the vessel containing a pipe having in its upper part a boiling device and its lower part being enlarged to cover at least a portion of the semipermeable membrane.

5. An absorption device for refrigeration installations, comprising a vessel containing a liquid and having an outlet at the top thereof for the refrigerating medium, a heating device in the vessel, a tubular body in the vessel and surrounding the heating device in spaced relation therewith, means in the lower part of the vessel into which the refrigerating medium returns to the vessel, said means being composed of a material which will permit the passage therethrough of the refrigerating medium as a gas but prevent the passage therethrough of any water, and a filter at the top of the vessel to prevent the passage of any water with the refrigerating medium.

6. An absorption device for refrigeration installations, comprising a vessel containing a liquid and having an outlet at the top thereof for the refrigerating medium, a heating device in the vessel, a tubular body in the vessel and surrounding the heating device in spaced relation therewith, and means in the lower part of the vessel into which the refrigerating medium returns to the vessel, said means being composed of a material which will permit the passage therethrough of the refrigerating medium as a gas but prevent the passage therethrough of any water, and said tubular body having a funnel shape at the lower end and into which the means extends whereby when the liquid is heated by the heating device it will circulate upwardly through the tubular body and then down between the outside of the tubular body and the vessel to again enter the tubular body.

ERNST SANDER.
